George Page of Keene, New Hampshire
Letters Patent

The Schedule referred to in these Letters Patent and making part of the same containing a description of the works of the said George Page himself of his improvement in the machine for sawing wood.

To all persons to whom these presents shall come. Be it known that I George Page of Keene, in the County of Cheshire, and State of New Hampshire have invented and made a new and useful improvement in the method of mortising by a machine, which machine is described as follows, viz.

The bottom consists of two pieces of flat wood, four inches wide, three inches thick, one piece three feet long. The other piece three feet and four inches. These are locked together crossing each other at right angles, the place of intersection in the shortest piece being at equal distances from each end, and in the longest piece about two feet from one end, the short end is at the front of the machine.

At the place of intersection a mortise is made, into which by a tenon is fixed an upright post four inches square and seven feet high from the bottom of the sill. This post is kept fast and supported by four braces from the sill. Beginning at three inches from the top of the sill a mortise is made in the ^{upper part of the} longest sill, through this post one inch wide and eleven inches long. Into the longest end of the long sill is fixed by a mortise and tenon, an upright post four inches wide two inches thick and ten inches high from the bottom of the sill. In the top of this post one end of a bar is inserted a pivot passing through the post and end of the bar, which bar is three feet long, one inch thick and three inches wide, and passes through the mortise in the post and has upon the other end a piece of timber four inches square and one inch, upon which to place the feet six inches above the mortise in the post another mortise is made through it in the same direction, five eighths of an inch wide and fifteen inches long, through this mortise passes an iron screw the bolt eight inches long,

with a strong collar and nail on one end, the other end passing through a piece of timber called the mortise. This mortise, two feet three inches long and four inches square, is bolted upon and which is fastened by an inch wide diameter plates through the middle of the rest and is made fast by a square head. On the back side of this rest are firmly secured two pieces of board four inches apart, the interval being in the middle of the rest. Apertures of the said bolt, screw and nail the rest may be made fast at any desirable height, and the two pieces of board, one on each side of the post, a pint in keeping it firm. A board three and a half inches wide of the same length as the rest is let into the post even with the face of it, crooping it. The upper edge lies in a bevel above the top of the mortise, the lower edge of course one and a half inch below, the board being cut away where it comes thru mortise. One inch above the top of the board on one side of the post a chisel one inch square and about three inches long is secured firmly to the post and the timber to be mortised from riding by the operation of the machine. Four feet three inches from the bottom of the sill a brace of the size of the post and three feet long is inserted into the post inclining forward at an angle of thirty two degrees from a horizontal line. This brace is fastened to the post by a short girl four inches square seventeen inches from the toe of the brace to the top of the girl. Through the brace and the girl, mortises are made next to the post three inches long measuring horizontally. Beginning five feet nine inches from the bottom of the sill, or one inch above the top of the girl, another mortise is made through the post in the same direction as the others one inch wide and eight inches long. These inches wide and one inch thick, it is mortised in the brace and fastened by a pin or pint. From this line to the lower part described passing a rod with a chisel on each end, by which to plane the two ends of the rod are attached to the two braces, several holes are made through each brace, the hole nearest the post being one and a half inch from the post and the others being one and a half inch from each other. These holes are to receive the pins passing through

holes in the ends of the clevises, and by attaching the ends of the rods to different places on the clevises, different purchases and motions may be obtained. Three inches and a half below the top of the brace a mortise is made through it of eight inches, one and a half inches square, into this mortise is inserted a spring made of hickory, ash or other elastic timber three feet long from the brace. The end of this spring and the end of the upper brace is connected by a leather strap having a buckle by which it may be tightened or loosened at pleasure. About three feet four inches above the top of the stirrups or about four inches above the bound place set off the post as above described on the right hand side of the post is made a groove about one and a half inches wide and half an inch deep - from the middle of this groove another is made into the front side of the post half an inch wide and one inch deep, and extending to within one inch of the other, left side of the post. The groove receives a cast iron box thus described; The side which when placed on the right side, is about one and a half inches wide, and five and a half inches long, and the thickness of the side is about half an inch. This side fits into the groove on the side of the post. From one end, the front end of this iron box a piece half an inch thick, and two and a half inches square which is inserted in the groove on the front side of the post. Through the center of this square is a round hole about one inch in diameter, the hole of which when the box is placed, appears in sight. Back of this square through the side above described, in the middle thereof is a mortise two inches long and three eighths of an inch wide. Through this mortise and through the post passes a bolt having a head on one end and a screw and nut on the other, by means of which the cast iron box may be secured, and moved back and forward a little at pleasure. Two feet above this box another similar one is placed in the same manner. The part of the machine next to be described is a round iron slide about two feet and one half long and one inch in diameter - on one end of this slide, through it and a strap of iron in the form of a ring, is attached by means of a

down the head of which is within the chain and the same enters the end of the slide passing through a hole in the head of the clevis. This hole in the clevis is made so large that the end may be turned. This clevis passes up on each side of the lever near the post, and is secured by a ^{cup} pin. About four inches from the other end the lower end of the slide a thumb piece is attached to it by which the slide may be turned. Half an inch above the thumb piece, a hole is made through the slide of the size of a large wire; four inches above this hole another, and into these holes later are inserted a wire bent at right angles so that the wire lays along the side of the slide - into the lower end of the slide is made a socket two inches deep to receive the shank of a chisel. At the extremity of the socket or top of the slide when inserted a hole is made through the slide for the purpose of driving out the chisel. This slide passes through the round hole in the upper cast iron box, through the mortise in the post above described, through the mortise in the brace and through the hole in the lower cast iron box. On each side of the slide are placed about two inches below the brace two small steel springs are inserted in holes made through the post. These springs project in front and on the inner side of each are small fluted groves made to receive the wire attached to the slide - by means of the thumb piece the slide may be turned half round, and the wire falling into the groove of one of the other spring fastens it. The socket in the lower end of the slide is turned to receive the shank of the chisel. The chisel to be fit the socket to be formed after the fashion of the chisel used for mortising, and be four inches in length exclusive of the shank. By turning the chisel in the socket flutings are made to the front to be used for cutting dove-tail mortises, and side wise to the front in cutting mortises for door posts, cabinet work window blinds, &c. In the same socket by taking out the chisel after cutting the mortise an iron driver with a round shank is to be inserted to drive or force the chisel out of the mortise. The driver is to be made of the same length of the chisel.

17484

315

about as thick as the chisel is wide, and about half an inch in width to be flat upon the lower end.

Operation of the machine. The moveable slide is first adjusted to the dimension of the timber or wood to be mortised which is easily done. The bands, on each side of the post, keeping it at right angles with the post. The rest is made fast by the screw and nut at the proper distance to admit the timber or wood to be mortised between the upper side of the rest and the lower end of the slide upon the post. To make the communication the wood to be mortised is placed upon the rest and the chisel set to cut either right or left head of the mortise, the iron upon the side of the slide in the groove of one of the steel springs, guiding the slide in the operation of the machine. The foot is applied to the lower lever and pressed down, the lower lever and upper lever being connected by the rod and chain, as the lower lever is pressed down it drives the slide down the upper lever to which the slide and a head are attached; and drives the chisel into the wood in proportion to the force applied by the foot of the operator. As the weight of the foot is withdrawn the spring at the top of the machine which is attached to the upper lever by the leather strap receives, by its elasticity and withdrawal, the chisel from the wood. The wood or timber is then moved by the hand of the operator and the foot applied as before and so on till one head of the mortise is finished. By means of the thumb piece the slide is then turned half round and the iron upon the slide set in the groove in the other steel spring and the other head of the mortise made by a similar operation.

To make the dovetail mortise the chisel is turned in the socket so that it is flatwise or face to the front, and the timber or board having the dovetail first sawed is presented endwise to the machine and the power is applied, and the operation carried on as before until the mortise is cut out. The slide not requiring to be turned in cutting this kind of mortise. To use the driver the chisel is taken from the socket and the driver inserted, the

and is let down and a block placed upon the rest with a hole made in the block to let the chip fall through. The draw is forced through the mortise in the same manner as the chisel is forced into the wood. My improvement consists in these, vary motion of the slide, the quoyners, the springs, and ground. Also in the clevis and pins upon the two ends of the end of the holes in the two boxes, by means of which the power and motion of the machine may be increased or diminished at the pleasure of the operator. Also in the round work in the slide, and round shank of the chisel by which the dovetail mortise is cut, and also by fixing to the machine a chisel, by which the chips are cleared from the mortise.

In testimony that the foregoing is a true specification of my said improvement, as described I have hereunto set my hand this twenty seventh day of February in the year of our Lord one thousand eight hundred and thirty three.
